RUG MAKING IMPLEMENT

Signe Charlotta Olsson, Stockholm, Sweden

Application July 13, 1948, Serial No. 38,522
In Sweden August 28, 1947

3 Claims. (Cl. 112—9)

1

The present invention relates to a method for the manufacture of articles, such as rag-rugs, drapery, and plaids for children, and to a device for carrying out the method. The object of the invention is mainly to manufacture such domestic craft articles very quickly in a simple and inexpensive way by means of a common sewing-machine and the proposed device according to the invention.

The invention is substantially characterized by the fact that the articles are manufactured by placing a support, e. g. a rug bottom of jute fabric, under the pressing foot of a sewing machine, whereafter a forked member is inserted between

2

ment shown in Figs. 1 and 2 is intended for the manufacture of rag-rugs while the embodiment shown in Figs. 3 and 4 is intended for the manufacture of fringes. Thus, the embodiment shown in Figs. 5 and 6 can be used for the manufacture of rag articles as well as of fringes.

A rag-rug is manufactured for instance in the following manner. Yarn or strips cut from old or new pieces of cloth, are wound around the fork along the entire length of the fork. After the yarn or the strips have been wound on the fork—one or more yarns, for instance up to 6 different kinds of yarns, according as a thinner or thicker rug or different colours are desired.

member being forked about the one half of its length by a stitch-receiving gap, the plane of said forked part of said member forming an obtuse angle with respect to the plane of the remaining unforked part of said member, said unforked part forming an inclined rigid mandrel for receiving the yarn-loops to be fed down to said forked part for stitching.

2. A rug making device comprising a rectangular plate-member, said member being bent to an obtuse angle along a transverse line at substantially the half of the length thereof, the one end portion of said member being longitudinally forked by a stitch-receiving gap ending near said transverse line.

3. A rug making device comprising a rectangular plate-member being substantially Z-shaped

in side view and having at least one of its free shanks forked by a stitch-receiving gap, the angle between each of said shanks and the middle-most portion of said plate-member being obtuse.

SIGNE CHARLOTTA OLSSON.
